INSIDE TUBING CUTTER

Ernest E. Anderson, Oklahoma City, Okla., assignor to Baash-Ross Tool Company, Los Angeles, Calif., a corporation of California

Application April 14, 1939, Serial No. 267,875

12 Claims. (Cl. 164—0.7)

This invention relates to a well tool and relates more particularly to a tool for cutting tubing, drill pipe, casing and other tubular objects in wells. A general object of this invention 5 is to provide a well tool of the character referred to that is simple and sturdy in construction and that is positive and dependable in operation.

Tools known as inside cutters are employed in wells to cut or sever tubing, casing, drill pipe, etc. to facilitate their removal from the wells. In operating the cutting tools it is sometimes impossible to determine when the cut is completed and the pipe or tubing is severed. Following the cutting operation an attempt is usually made to withdraw the severed portion of the pipe or tubing from the well. If it is found that the severed portion of the pipe or tubing cannot be pulled from the well the success of the cutting operation cannot be determined.

Another object of this invention is to provide 10 another object of this invention is to provide an inside cutting tool that provides a definite signal or indication at the completion of the cutting operation to give positive assurance that the pipe or tubing has been fully cut or severed.

Another object of this invention is to provide 15 an inside cutter embodying cutters or knives that are fully and automatically retracted at the completion of the cutting operation, but not until the completion of the cutting operation, to relieve the resistance to rotation of the operating string thereby indicating to the operator that the cutting operation is completed.

Another object of this invention is to provide 20 an inside cutter that is such that the operator may keep informed of the extent of projection of the cutters and therefore may be advised of the progress of the cutting operation.

Another object of the invention is to provide 25 a cutting tool of the character mentioned embodying novel means for evenly and smoothly advancing or extending the cutters outwardly as the operating string is rotated.

Another object of this invention is to provide 30 a cutting tool of the character mentioned that may be easily and inexpensively conditioned to cut tubular objects of different diameters and of different wall thicknesses.

The various objects and features of my invention will be fully understood from the following 35 detailed description of a typical preferred form and application of the invention, throughout which description reference is made to the accompanying drawings, in which:

Fig. 1 is a side elevation of the tool of the 40 invention in position in a tubing, showing the

tubing in longitudinal cross section. Fig. 2 is an enlarged longitudinal detailed sectional view of the upper portion of the tool with the parts in the unactuated positions and illustrating a portion of the tool in side elevation. Fig. 3 is 5 an enlarged longitudinal detailed sectional view of the lower portion of the tool illustrating the holding means in the actuated condition. Fig. 4 is a view similar to Fig. 2 illustrating the mandrel in side elevation and showing the cutters 10 in a partially projected condition. Fig. 5 is an enlarged transverse detailed sectional view taken as indicated by line 5—5 on Fig. 2. Fig. 6 is an enlarged horizontal detailed sectional view taken as indicated by line 6—6 on Fig. 4. Fig. 7 is an 15 enlarged horizontal detailed sectional view taken as indicated by line 7—7 on Fig. 2. Fig. 8 is a fragmentary longitudinal detailed sectional view illustrating the manner in which the cutters retract above the actuating ribs at the completion 20 of the cutting operation and Figs. 9 and 10 are enlarged horizontal detailed sectional views taken as indicated by lines 9—9 and 10—10, respectively, on Fig. 1.

I will herein refer to the device of the present 25 invention as a tubing cutter and will describe the tool as operating to cut a tubing in a well. The invention may be embodied in tools for cutting other tubular objects, for example, drill pipe, well casing, etc., and it is to be understood 30 that the invention is not to be construed as limited or restricted to the specific form or application herein described.

The inside cutter of the present invention 35 illustrated in the drawings may be said to comprise, generally, a body 10, projectable knives or cutters 11 carried by the body 10, a threaded mandrel 12 extending through the body 10 and operable to actuate the cutters 11, a nut 13 having threaded cooperation with the mandrel 12 40 and releasable means 14 for holding the nut 13 against rotation whereby rotation of the mandrel 12 projects the cutters 11.

The body 10 is an elongate tubular member or assembly adapted to extend into the tubing T 45 with suitable clearance. In the preferred construction the body 10 comprises two sections, namely, an upper section 15 and a lower section 16. The sections 15 and 16 are connected by spaced longitudinal screws 17 passed through 50 openings 18 in the upper section 15 and threaded into sockets 19 in the lower section 16. The opposing ends of the connected body sections 15 and 16 are spaced apart to leave a gap or space 55 for the cutters 11. The two body sections 15

and 16 may be cylindrical and of uniform diameter. A pin 20 of reduced diameter is provided on the lower end of the lower body section 16.

The cutters 11 are projectable from the body 10 and are operable by rotation of the body to cut through the tubing T. In the preferred form of the invention there is a plurality of circumferentially spaced cutters 11 provided in the space between the two body sections 15 and 16. 5 As illustrated in the drawings, there may be three like cutters 11. The cutters 11 are longitudinally curved and are provided at their outer free corners with projecting sharpened blades or cutting parts 21. The cutters 11 are supported to 10 pivot about vertical axes. Openings 22 in the inner parts of the cutters 11 may receive the above mentioned screws 17 whereby the screws serve to pivotally mount the cutters 11. The cutters 11 are normally retracted to be entirely 15 within the space between the two body sections 15 and 16.

The mandrel 12 is an elongate member adapted to be connected with the lower end of a well string or operating string S. The mandrel 12 passes downwardly through the tubular body 25 sections 15 and 16 with suitable clearance and continues beyond the body to cooperate with the nut 13 and to carry the means 14 as will be subsequently described. In accordance with the invention the portion of the mandrel 12 extending through the lower body section 16 and the nut 13 is threaded. The thread 9 on the mandrel 12 is continuous and has a gradual or slight pitch. A suitable guide member or head 23 may be provided on the extreme lower end of the mandrel 12.

The mandrel 12 carries parts for cooperating with the cutters 11 to effect the projection of the cutters. A plurality of longitudinally extending tapered splines or ribs 24 is provided on the mandrel 12. The ribs 24 are circumferentially spaced about the mandrel 12 and there is a rib 24 for engaging each cutter 11. The ribs 24 are of substantial length and their outer surfaces or edges 25 are curved or rounded to substantially conform to the inner edges of the cutters 11. The outer surfaces 25 of the ribs 24 slope downwardly and inwardly relative to the longitudinal axis of the mandrel 12. It is preferred to removably secure the ribs 24 to the mandrel 12 whereby they may be replaced by ribs capable of projecting the cutters 11 different distances. In the construction illustrated the ribs 24 are set in longitudinal grooves 26 in the mandrel 12 and may be temporary or detachably secured in the grooves by welding or the like.

With the parts in the initial or normal positions the ribs 24 extend into slots 27 in the upper body section 15. The slots 27 are adapted to receive or pass the ribs 24 with suitable clearance and the cooperation of the sides of the ribs 24 with the side walls of the slots 27 may assist in transmitting rotation from the mandrel 12 to the body 10. Slots 28 are provided in the lower body section 16 to receive the ribs 24 during the actuation of the tool. The slots 28 are adapted to freely receive the ribs 24 and the engagement of the ribs with the side walls of the slots 28 may assist in transmitting turning forces 60 from the mandrel 12 to the body 10. The outer walls or bottom walls of the slots 28 may taper downwardly and inwardly to be engaged by the active surfaces 25 of the ribs 24 following the completion of the cutting operation to limit the downward travel of the ribs.

In accordance with the invention the tapered ribs 24 are operable to project the cutters 11 a distance sufficiently great to completely cut through the wall of the tubing T. It will be understood how the inclined surfaces 25 of the ribs 24 cooperate with the cutters 11 during downward movement of the mandrel 12 relative to the body 10 to feed or project the cutters 11. The parts are related and proportioned so that the upper ends of the ribs 24 pass downwardly beyond the cutters 11 simultaneously with or immediately following the completion of the cut.

The invention provides means for automatically returning the cutters 11 to their retracted positions at the completion of the cut or when the ribs 24 pass below the cutters 11. The means for restoring the knives or cutters 11 are preferably spring means. In the construction illustrated vertically arranged leaf springs 33 are secured to the upper body section 15 and extend downwardly to have their lower parts bear inwardly against the outer sides of the pivoted cutters 11. When the upper ends of the ribs 24 pass the cutters 11 at or immediately following the completion of the cut the springs 33 pivot the knives or cutters 11 inwardly to the retracted positions illustrated in Figs. 4 and 5 of the drawings, where they lie against the mandrel 12. The retraction of the cutters 11 by the springs 33 of course fully disengages the cutters from the tubing T. Upon the retraction of the cutters 11 from the tubing T, at the completion of the cut, substantially all resistance to rotation of the operating string S is relieved indicating to the operator that the cut has been completed.

The nut 13 has threaded engagement with the mandrel 12 and is rotatably connected with the body 10 whereby rotation of the mandrel relative to the nut feeds the mandrel longitudinally to effect the actuation of the cutters 11. The nut 13 is preferably provided at one end of the body 10. In the preferred construction illustrated the nut 13 is at the lower end of the body 10. A socket 29 in the upper end of the nut 13 receives the pin 20 on the lower body section 16. Series of balls 30 cooperate with opposing races 31 in the side and bottom walls of the socket 29 and the side and bottom surfaces of the pin 20 to connect the body 10 and nut 50 13 for free relative rotation. A longitudinal opening 32 extends through the nut 13 to receive or pass the mandrel 12. A thread is provided on the wall of the opening 32 to mate with the thread 9 on the mandrel 12.

The means 14 is in the nature of a slip means and tail-piece means engageable with the interior of the tubing T to hold the nut 13 against movement whereby the threaded mandrel 12 may be rotated to project the pivoted cutters 11. The means 14 is located below the body 10 and is connected with the nut 13. In the preferred construction the means 14 includes a sleeve 34 shiftably surrounding the mandrel 12 below the nut 13. The upper portion of the sleeve 34 is threaded in the nut 13 so that the sleeve is rigid with the nut. It will be observed that the sleeve 34 is suspended from the body 10 through the nut 13. The sleeve 34 has an intermediate portion 35 of enlarged diameter provided with downwardly and inwardly inclined surfaces 36. Slips 37 are shiftable on the inclined surfaces 36. Dove-tailed tongue and groove connections 38 are provided between the slips 37 and the sleeve portions 35 whereby the slips are held against

lateral shifting and displacement. The outer sides of the slips 37 have wickers or teeth 39 for gripping the inner surface of the tubing T. The teeth 39 are grooved or cut vertically as well as horizontally so that the slips 37 are operable to hold the sleeve 34 against turning movement and longitudinal movement.

The means 14 further includes a spring assembly or tail-piece for controlling the slips 37. Rings 40 and 41 are shiftable on the sleeve 34 above and below its enlarged portion 35. Outwardly bowed leaf springs 42 extend between and connect the rings 40 and 41. The springs 42 are adapted to frictionally engage the interior of the tubing T to resist movement of the rings 40 and 41. Operative connections are provided between the rings 40 and 41 and the slips 37 whereby the engagement of the springs 42 with the tubing T resists movement of the slips 37. Fingers 43 and 44 extend longitudinally from the rings 40 and 41, respectively, and pass through suitable grooves 45 in the enlarged sleeve portion 35. The end portions of the fingers 43 and 44 cooperate with notches 46 in the upper and lower ends 25 of the slips 37. The cooperation of the fingers 43 and 44 with the notches 46 is such that the springs 42 frictionally bearing in the tubing T resist movement of the slips 37 when the body 10 and the sleeve 34 are shifted to actuate the slips.

Releasable means is provided to hold the sleeve 34 and the spring tail-piece assembly against relative longitudinal movement in a relationship where the slips 37 are retracted so that the tool may be easily run through the well and freely entered in the tubing T. This means includes a control member 48 rotatably mounted on the lower portion of the sleeve 34. A pin 49 may pass through an opening in the member 48 to cooperate with an annular groove 50 in the sleeve 34. The engagement of the pin 49 in the groove 50 prevents longitudinal shifting of the member 48 on the sleeve 34 but allows relative rotation between the sleeve and the member. A socket 51 is provided in the lower end of the lower ring 41 and a pin 52 on the member 48 is releasably threaded in the socket 51. The threads of the socket 51 and the pin 52 preferably have a much greater pitch than the threads 9 of the mandrel 12 and the threads of the nut 13. A longitudinal slot 53 enters the member 48 from its lower end and a pin 54 on the mandrel 12 engages in the slot 53. The pin 54 cooperating with the slot 53 is operable to transmit turning movement from the mandrel 12 to the member 48. When the pin 52 of the member 48 is threaded in the socket 51 the slips 37 are in a retracted condition clear of the interior of the tubing T. It will be understood how the mandrel 12 may be turned by means of the string S to thread the pin 52 from the socket 51.

In the use or operation of the tool of this invention the parts may be assembled as illustrated in Fig. 1 of the drawings and the mandrel 12 may be connected with the string S preparatory to lowering the tool into the well. The pin 52 is initially threaded in the socket 51 so that the slips 37 are fully retracted and the springs 33 serve to hold knives or cutters 11 in their fully retracted positions. Thus the tool may be run through the well without danger of the slips 37 or the knives 11 interfering with its movement. When the tool or cutter has reached the correct or selected position in the tubing T the string S is rotated to thread the pin 52 from the

socket 51. The springs 42 cooperating with the tubing T resist turning of the ring 41 so that the pin 52 may be readily unthreaded from the socket. When the mandrel 12 is rotated to unthread the pin 52 from the socket 51 the mandrel is threaded a short distance through the nut 13 and the ribs 24 may cause a slight outward pivoting of the cutters 11. However, due to the marked difference in the pitch of the threads 9 on the mandrel 12 and the threads of the socket 51 and the pin 52 the mandrel is threaded but a short distance at this time. Following the release of the pin 52 from the socket 51 the mandrel 12 is lowered so that the surfaces 36 cooperate with the slips 37 to actuate them outwardly against the tubing T. The springs 42 frictionally bearing in the tubing resist downward movement of the slips 37 when the mandrel is moved to actuate the slips. Following the setting of the slips 37 as just described the string S is rotated to thread the mandrel 12 down through the nut 13. The slips 37 gripping the interior of the tubing T serve to hold the sleeve 34 and the nut 13 against rotation and downward movement while the mandrel is being threaded through the nut.

Downward threading of the mandrel 12 is accompanied by downward movement of the ribs 24 and is accompanied by rotation of the body 10. The ribs 24 cooperate with the slots 27 and 28 to transmit the turning movement from the mandrel to the body 10. The inclined surfaces 25 of the ribs 24 cooperate with the knives or cutters 11 to feed or pivot the cutters outwardly. Thus the cutters 11 carried by the rotating body 10 are fed outwardly against the interior of the tubing T as the mandrel 12 is threaded down through the nut 13. The operator may be informed of the number of rotations of the mandrel 12 required to project the cutters 11 a given distance and the operator may in this manner be aware of the depth of the cut and the condition of the tool at all times during its operation.

The rotation of the string S and the downward threading of the mandrel 12 is continued until the upper portions of the ribs 24 are in cooperation with the knives or cutters 11 at which time the knives will have fully cut through the wall of the tubing T. Substantially simultaneously with the completion of the cut the upper ends of the ribs 24 pass below the cutters 11 and the springs 33 suddenly retract the cutters from the tubing T. This retraction of the cutters 11 is accompanied by the removal of substantially all resistance to rotation of the string S and this informs the operator that the cut is completed. When the cut has been completed and the knives or cutters 11 retracted, as just described, the tool may be withdrawn from the well. When the string S is raised the springs 42 cooperate with the tubing T to resist upward movement of the slips 37 and the dove-tailed connections 38 between the slips and the sleeve portion 35 cause retraction of the slips. The slips 37 and the knives 11 are fully retracted when the tool is withdrawn from the well.

Having described only a typical preferred form and application of my invention, I do not wish to be limited or restricted to the specific details herein set forth, but wish to reserve to myself any variations or modifications that may appear to those skilled in the art or fall within the scope of the following claims.

Having described my invention, I claim:

1. A tool for cutting a tubular object in a well comprising a body adapted to be entered into

the object, the body having a groove, a cutter carried by the body and projectable into cutting engagement with the tubing, a nut member rotatably connected with the body, means operable to hold the nut member against movement, a mandrel threaded through the nut member, and a rib part on the mandrel engaging in the groove to cause the body to rotate with the mandrel and cooperable with the cutter to project the cutter when the mandrel is threaded through the nut member.

2. A tool for cutting a tubular object in a well comprising a body adapted to be rotated in the object, cutting means carried by the body for projection into cutting engagement with the object, an inclined part moved during rotation of the body to feed the cutting means outwardly to make an annular cut through the wall of the object and having an end substantially normal to the direction of its movement movable out of engagement with the cutting means at the completion of the cut to free the cutting means for restoration, and means for restoring the cutting means at the completion of the cut whereby resistance to rotation of the body is relieved at the completion of the cut.

3. A tool for cutting a tubular object in a well comprising a body adapted to be rotated in the object, a mandrel for rotating the body, means operable by rotation of the mandrel for moving the mandrel longitudinally relative to the body, cutting means carried by the body for projection into cutting engagement with the object, an inclined part on the mandrel operable during said longitudinal movement of the mandrel to feed the cutting means outwardly to make an annular cut through the wall of the object and having an end substantially normal to the direction of said longitudinal movement movable out of engagement with the cutting means at the completion of the cut freeing the cutting means for restoration, and a spring for restoring the cutting means at the completion of the cut whereby the resistance to rotation of the mandrel is relieved at the completion of the cut.

4. A tool for cutting a tubular object in a well comprising a body adapted to be rotated in the object, cutting means carried by the body for projection into cutting engagement with the object, a mandrel, thread means for advancing the mandrel when the same is rotated, and a part on the mandrel cooperable with the cutting means to project the same when the mandrel is advanced and adapted to move free of the cutting means by said advancement of the mandrel when the cut in the object is completed.

5. A tool for cutting a tubular object in a well comprising a body adapted to be rotated in the object, cutting means carried by the body for projection into cutting engagement with the object, a mandrel, thread means for advancing the mandrel when the same is rotated, and a part on the mandrel for rotating the body together with the mandrel and operable to feed the cutting means outwardly to cut through the object when the mandrel is advanced, and means for retracting the cutting means from the object when the cut in the object is completed.

6. A tool for cutting a tubular object in a well comprising a body adapted to be entered into the object, a cutter carried by the body and projectable into cutting engagement with the tubing, a nut member rotatably connected with the body, means operable to grip the object to hold the nut member against movement, a man-

drel having threaded engagement with the nut member to be fed longitudinally when rotated, and a part on the mandrel engageable with the cutter to project the same as the mandrel is fed longitudinally and adapted to move past the cutter to free the same for retraction when the mandrel has been fed a given distance.

7. A tool for cutting a tubular object in a well comprising a body adapted to be entered into the object, a cutter carried by the body and projectable into cutting engagement with the tubing, a nut member rotatably connected with the body, means operable to grip the object to hold the nut member against movement, a mandrel having threaded engagement with the nut member to be fed longitudinally when rotated, a part on the mandrel engageable with the cutter to project the same as the mandrel is fed longitudinally and adapted to move past the cutter to free the same for retraction when the mandrel has been fed a given distance, and spring means for retracting the cutter.

8. A tool for cutting a tubular object in a well comprising a body adapted to be entered into the object, a cutter carried by the body and projectable into cutting engagement with the tubing, a nut member rotatably connected with the body, means operable to grip the object to hold the nut member against movement, a mandrel having threaded engagement with the nut member to be fed longitudinally when rotated, and a tapered longitudinal rib on the mandrel for projecting the cutter as the mandrel is fed longitudinally and adapted to move past the cutter to free the same for retraction when the mandrel has been fed a given distance.

9. A tool for cutting a tubular object in a well comprising a body adapted to be entered into the object, a cutter carried by the body and projectable into cutting engagement with the tubing, a nut member rotatably connected with the body, means operable to grip the object to hold the nut member against movement, a mandrel having threaded engagement with the nut member to be fed longitudinally when rotated, and a tapered longitudinal rib on the mandrel for projecting the cutter as the mandrel is fed longitudinally and adapted to move past the cutter to free the same for retraction when the mandrel has been fed a given distance, the body having a groove shiftably receiving the rib to rotate with the mandrel.

10. A tool for cutting a tubular object in a well comprising a body adapted to be entered into the object, a cutter carried by the body and projectable into cutting engagement with the tubing, a nut member rotatably connected with the body, means operable to grip the object to hold the nut member against movement, a mandrel having threaded engagement with the nut member to be fed longitudinally when rotated, means initially holding the last mentioned means inoperative releasable by manipulation of the mandrel, and a part on the mandrel engageable with the cutter to project the same as the mandrel is fed longitudinally and adapted to move past the cutter to free the same for retraction when the mandrel has been fed a given distance.

11. A tool for cutting a tubular object in a well comprising a body adapted to be entered into the object, a cutter carried by the body and projectable into cutting engagement with the tubing, a nut member rotatably connected with the body, slip means operable to grip the object to hold the member against movement and to

- support the body against downward movement, a mandrel having threaded engagement with the member to be fed downwardly when rotated, a wedge part on the mandrel operable to project the cutter as the mandrel is fed downwardly and adapted to pass out of engagement with the cutter when the mandrel has been fed a given distance, and means for retracting the cutter when the wedge part leaves the same.
- 10 12. A tool for cutting a tubular object in a well comprising a body adapted to be entered into the object, a cutter carried by the body and projectable into cutting engagement with the tubing, a nut member rotatably connected with the body, slip means operable to grip the object to hold the member against movement and to support the body against downward movement, a releasable control for holding the slip means in a retracted condition, a mandrel having threaded engagement with the member to be fed downwardly when rotated, a wedge part on the mandrel operable to project the cutter as the mandrel is fed downwardly and adapted to pass out of engagement with the cutter when the mandrel has been fed a given distance, and means for retracting the cutter when the wedge part leaves the same.

ERNEST E. ANDERSON.
